K. MUHLEISEN

HEAT EXCHANGE APPARATUS

Filed March 29, 1923

BY *Karl Muhleisen*
Cyrus V. Anderson
ATTORNEY.

UNITED STATES PATENT OFFICE.

KARL MUHLEISEN, OF PHILADELPHIA, PENNSYLVANIA, ASSIGNOR TO SCHUTTE AND KOERTING COMPANY, OF PHILADELPHIA, PENNSYLVANIA, A CORPORATION OF PENNSYLVANIA.

HEAT-EXCHANGE APPARATUS.

Application filed March 29, 1923. Serial No. 628,430.

To all whom it may concern:

Be it known that I, KARL MUHLEISEN, a citizen of the United States, and a resident of Philadelphia, in the county of Philadelphia and State of Pennsylvania, have invented an Improvement in Heat-Exchange Apparatus, of which the following is a specification.

My invention relates to heat exchange apparatus in which each unit or apparatus comprises a tubular casing in which casing is situated a plurality of tubes the opposite ends of which are secured in tube plates, and the general object of the invention is to provide a novel construction of means whereby there may be relative movement between the inclosing casing and the tubes therein due to inequalities of expansion of the tubes and their surrounding casing.

A further object of the invention is to provide an improved and novel construction of means for retaining packing in operative relation to one of the tube plates and for adjusting and tightening the same in case adjustment and tightening may become necessary.

It frequently happens that a plurality of heat exchange apparatus units are connected together so that the fluids between which an interchange of heat is to be effected flow in opposite directions successively through the said units; hence it is a further object of my invention to connect the said units together in such manner that relative movement between the said connected units due to any inequalities in the expansion thereof shall not be interfered with.

To these and other ends my invention comprehends the construction as hereinafter fully described, particularly pointed out in the claims, and as illustrated in the accompanying drawing forming a part of this specification and in which I have illustrated one form of mechanical embodiment of heat exchange apparatus embodying my invention. However, it will be understood that my invention is susceptible of embodiment in other forms of construction than that shown and that changes in the details thereof may be made within the scope of the claims without departing from the said invention.

In the drawing:

Fig. 1 is a longitudinal sectional view of a heat exchange apparatus embodying my invention;

55

Fig. 2 is a transverse sectional view taken on the line 2—2 of Fig. 1; and

Fig. 3 is a plan view showing a plurality of apparatus or units, such as that shown in Fig. 1, connected together so as to constitute a unitary structure.

Referring to the drawing: 1 designates the exterior casing of a heat exchange apparatus unit, which casing, in the construction shown, is made up of a plurality of tubular members or sections *a*, *b*, *c* and *d*, as shown. Referring for the moment to the apparatus shown in Fig. 1 it will be noted that the member or section *a* is provided with a port 2 comprising a short tubular portion 70 having at its outer end a laterally extending flange 3. The outer end of the section *a* is closed by means of a head plate 4, in the usual manner. The inner end of the section *a* is provided with a laterally extending flange 5 which is situated in opposed relation with respect to a flange 6 upon the adjacent member or section *b*. These flanges are secured together by means of screw threaded bolts 7. 8 designates a relatively stationary tube plate the outer peripheral edge of which is clamped between the adjacent ends of the members or sections *a* and *b*. The tube plate 8 is provided with a series or plurality of openings therein in which one end of each of a plurality or series of tubes 10 is secured. At their opposite ends each of the said tubes 10 is secured in an opening in a tube plate 15 which is adapted for movement relatively to the section *d* within which it is situated. The peripheral surface of the tube plate is seated against an inwardly extending bearing rib 16 integral with the member *d*. The said tube plate 15 is provided at its peripheral edge with an outwardly extending flange 20 which is concentric with the member or section *d* and which is spaced from the inside surface thereof so as to leave or provide a pocket or chamber 21 within which a body 100 of packing 22 is situated. For the purpose of compressing and holding the packing 22

75

flange 5 which is situated in opposed relation with respect to a flange 6 upon the adjacent member or section *b*. These flanges are secured together by means of screw threaded bolts 7. 8 designates a relatively stationary tube plate the outer peripheral edge of which is clamped between the adjacent ends of the members or sections *a* and *b*. The tube plate 8 is provided with a series or plurality of openings therein in which one end of each of a plurality or series of tubes 10 is secured. At their opposite ends each of the said tubes 10 is secured in an opening in a tube plate 15 which is adapted for movement relatively to the section *d* within which it is situated. The peripheral surface of the tube plate is seated against an inwardly extending bearing rib 16 integral with the member *d*. The said tube plate 15 is provided at its peripheral edge with an outwardly extending flange 20 which is concentric with the member or section *d* and which is spaced from the inside surface thereof so as to leave or provide a pocket or chamber 21 within which a body 100 of packing 22 is situated. For the purpose of compressing and holding the packing 22

80

flange 5 which is situated in opposed relation with respect to a flange 6 upon the adjacent member or section *b*. These flanges are secured together by means of screw threaded bolts 7. 8 designates a relatively stationary tube plate the outer peripheral edge of which is clamped between the adjacent ends of the members or sections *a* and *b*. The tube plate 8 is provided with a series or plurality of openings therein in which one end of each of a plurality or series of tubes 10 is secured. At their opposite ends each of the said tubes 10 is secured in an opening in a tube plate 15 which is adapted for movement relatively to the section *d* within which it is situated. The peripheral surface of the tube plate is seated against an inwardly extending bearing rib 16 integral with the member *d*. The said tube plate 15 is provided at its peripheral edge with an outwardly extending flange 20 which is concentric with the member or section *d* and which is spaced from the inside surface thereof so as to leave or provide a pocket or chamber 21 within which a body 100 of packing 22 is situated. For the purpose of compressing and holding the packing 22

85

flange 5 which is situated in opposed relation with respect to a flange 6 upon the adjacent member or section *b*. These flanges are secured together by means of screw threaded bolts 7. 8 designates a relatively stationary tube plate the outer peripheral edge of which is clamped between the adjacent ends of the members or sections *a* and *b*. The tube plate 8 is provided with a series or plurality of openings therein in which one end of each of a plurality or series of tubes 10 is secured. At their opposite ends each of the said tubes 10 is secured in an opening in a tube plate 15 which is adapted for movement relatively to the section *d* within which it is situated. The peripheral surface of the tube plate is seated against an inwardly extending bearing rib 16 integral with the member *d*. The said tube plate 15 is provided at its peripheral edge with an outwardly extending flange 20 which is concentric with the member or section *d* and which is spaced from the inside surface thereof so as to leave or provide a pocket or chamber 21 within which a body 100 of packing 22 is situated. For the purpose of compressing and holding the packing 22

90

flange 5 which is situated in opposed relation with respect to a flange 6 upon the adjacent member or section *b*. These flanges are secured together by means of screw threaded bolts 7. 8 designates a relatively stationary tube plate the outer peripheral edge of which is clamped between the adjacent ends of the members or sections *a* and *b*. The tube plate 8 is provided with a series or plurality of openings therein in which one end of each of a plurality or series of tubes 10 is secured. At their opposite ends each of the said tubes 10 is secured in an opening in a tube plate 15 which is adapted for movement relatively to the section *d* within which it is situated. The peripheral surface of the tube plate is seated against an inwardly extending bearing rib 16 integral with the member *d*. The said tube plate 15 is provided at its peripheral edge with an outwardly extending flange 20 which is concentric with the member or section *d* and which is spaced from the inside surface thereof so as to leave or provide a pocket or chamber 21 within which a body 100 of packing 22 is situated. For the purpose of compressing and holding the packing 22

in place within the pocket 21 I have provided an adjustable member or device which comprises a ring 23 which is situated within or which projects into the pocket 21 above the packing 22 therein. The ring 23 is connected, integrally in the construction shown, with spaced bars 25, the outer ends of which are connected, integrally in the construction shown, to a flange 26 extending outwardly from an annular member 27 situated within and spaced from the interior surface of the outer end portion of the member or section *d* of the casing. The outer edge of the flange 26 contacts and fits closely but movably within the outer end portion of the said member or section *d*. The flange 26 and the annular member 27 form with the adjacent portion of the member or section *d* a pocket or chamber 30 within which is seated a body of packing material 31. Said packing material is adapted to be compressed and held in place within the pocket 30 by means of a flange 32, operating as a gland, which projects inwardly from the inner side of the head plate 33. The head plate 33 is of greater diameter than the exterior diameter of the member or section *d* so that the outer edge portion thereof projects beyond the outer edge of the adjacent end of the said member. The member *d* is provided adjacent its end with a laterally and outwardly extending flange 35 having screw threaded openings therein with which the screw threaded bolts 36 are adapted to engage for securing the said head plate 33 to the adjacent outer end portion of the member *d* with the gland 32 projecting into the pocket 30 previously referred to. The bolts 36 extend through openings adjacent the outer peripheral edge of the head plate 33. The screw threaded opening 37 in the head plate 33 is for the reception of an eyebolt or equivalent means to facilitate the handling of the said plate.

Preferably, though not necessarily, the outer side of the bearing rib 16 is inclined inwardly and at an acute angle to the axis of the apparatus, and the inner edge of the ring 23 is inclined downwardly and outwardly from such axis so that when the screw bolts 36 are tightened as may become necessary the tendency is to compress the packing 21 more firmly than otherwise might be the case against the outer peripheral surface of the flange 20.

It will also be noted that the outer side of the flange 26 is inclined outwardly and away from the axis of the apparatus, while the inner edge of the gland 32 is inclined inwardly with the result that upon the tightening of the screw bolts 36 for adjustment or tightening of the packing masses 31 and 22, the packing 31 is compressed more tightly than otherwise might be the case against the

adjacent inner surface of the member or section *d*.

It will be noted that the member or section *b* is provided with an outlet port 40 comprising a short tubular member having a laterally extending flange 41.

The member or section *d* is provided with ports 42 and 43. The ports 42 and 43 comprise short tubular sections having laterally extending flanges 44 at their outer ends, the adjacent edges of which may be integral as shown. Such integrality is not, however, essential or necessary. Oppositely disposed portions of the port 43 are flared outwardly as indicated at 45 so as to enlarge the opening into that portion of the section *d* within which the bars 25 are situated, so as to compensate for the retardation that might be offered by the said bars to the passage of a fluid therethrough.

Assuming that a hot fluid, such as oil, enters the port 2 from a source not shown; it will flow through the tubes 10 and into the chamber between the tube plate 15 and the head plate 33 and outwardly through the port 43. Simultaneously with the passage of the hot oil through the tubes 10 a counter-moving fluid, such as cold oil, is flowing through the casing in the opposite direction. Such counter-moving or flowing fluid is baffled from side to side of the casing by means of the baffle plates 50 which are situated at intervals within the casing and through which the tubes 10 extend in known manner. Assuming that the fluid, such as oil, which enters the port 42 is cold; it will be heated by heat transmitted to it from the hot oil (or other fluid) flowing in counter-direction through the tubes 10. The heated oil or other fluid is discharged from the casing through the port 40 and is conducted through a conduit (not shown) to any desired destination, not shown.

In case a plurality of heat exchange units are connected together to form a larger unit, as indicated in Fig. 3, the hot oil or other fluid, which flows through the tubes 10, is conducted from the first of the series of the units of the apparatus, which I have designated in Fig. 3 by the reference letter *A*, and thence successively through the tubes 10 of the successive apparatus *B*, *C* and *D*, finally issuing from the latter through an outlet port at 51, similar to the port 2.

In the case of an apparatus consisting of a plurality of units secured together as indicated in Fig. 3 the cold oil or other fluid which is adapted to be heated enters the member or unit *D* through a port at 52 similar to the port 40 and flows through the casings surrounding the tubes in the separate units *D*, *C*, *B*, *A* in counter-direction to the flow of hot fluid through the tubes 10, and finally is discharged at 40.

In the construction as illustrated in Fig. 3, comprising a plurality of single heat exchange units combined together so as to constitute a larger unitary structure, the units 5 A and B (which are identical with the remaining units C and D) are rigidly connected together at one end by securing together the flanges 44 upon the adjacent tubular ports 42 and 43 thereof. Such connection 10 may be effected by bolting or brazing or in any manner which may be preferred. At their opposite ends the members A and B are slidably connected. Such connection is effected by providing flanges 62 upon the 15 outer ends of the members or sections b through which slots are provided. Interposed between the said flanges is a pedestal 63 having flanges 64 at its opposite ends through which slots are provided. Bolts 65 20 extend through the slots in the flanges 62 and 64 and connect the same together. The connection is sufficiently loose to permit relative sliding movement between the separate units A and B. Similar connections are 25 effected between the separate units or members B and C and likewise between the separate units or members C and D, so that there may be relative sliding movement between the various members A, B, C and D, which 30 may be due to any inequalities of expansion thereof.

It will be seen that by my invention I have provided means whereby there may be relative movement between the tubes and the casings within which the said tubes are situated, and in the case of a structure comprising a plurality of heat exchange units secured together as described, and as shown in Fig. 3, there may be simultaneous relative movement between the said connected units.

It will also be seen that by my invention I have provided means whereby the two masses or bodies of packing material 22 and 45 31 may be simultaneously adjusted and compressed, and whereby also the body of packing which surrounds a portion of the said tube plate may be compressed firmly against the latter, and whereby the other body of 50 packing may be compressed firmly against the inner surface of the casing within which the tubes and the tube plate are situated. This latter feature of construction is of particular importance because it insures that 55 the fluid which may be flowing through the tubes 10 shall not become mixed with that flowing through the casing exteriorly of and surrounding the said tubes.

Having thus described my invention, what 60 I claim and desire to secure by Letters Patent is:

1. In heat exchange apparatus, the combination of a casing, a plurality of tubes therein, a tube plate relatively movable with 65 respect to the said casing to which one end

of each of said tubes is connected, the said tube plate having at its peripheral edge an outwardly extending flange which is spaced from the inner surface of the said casing, packing within the space between the said flange and the said casing, a head plate for closing the adjacent end of said casing, which head plate is adjustable axially of said casing and means intermediate the said head plate and the said packing whereby upon adjustment of the said head plate inwardly the said packing is compressed. 70 75

2. In heat exchange apparatus, the combination of a casing having an inwardly extending annular rib upon its inner surface near one end thereof, a plurality of tubes situated within said casing, a tube plate adapted to have relative movement with respect to said casing, the peripheral surface of said tube plate contacting with the inner surface of said rib, and one end of each of said tubes being secured in openings through said tube plate, and the said tube plate having a flange adjacent its peripheral edge, which flange extends outwardly and forms with the said rib and the adjacent portion of the said casing a pocket, packing material within said pocket, a head plate for closing the adjacent end portion of said casing, a member interposed between the said head plate and the said packing, said member comprising an outer portion forming with the adjacent inner portion of the said casing a pocket, packing material within said pocket, and the said head plate having an inwardly extending flange in engagement with the last mentioned packing, and means for adjusting the said head plate toward the end of the said casing to exert pressure upon the last mentioned packing and upon the said intermediate member, substantially as described. 80 85 90 95 100 105

3. In heat exchange apparatus, the combination of a casing having tube plates adjacent the opposite ends thereof, which plates are provided with openings therethrough, and one of which is stationary and the other one of which is movable relative to the casing, a plurality of tubes within the casing having their opposite ends secured in the openings in said plates, and a portion of the peripheral edge of the said relatively movable plate being spaced from and forming with a portion of said casing a pocket, a head plate for closing the end of said casing adjacent the said relatively movable tube plate, a member intermediate the said head plate and the said relatively movable tube plate, the outer end portion of said member forming with an adjacent portion of the said casing a pocket, a packing mass in each of the said pockets, and a flange extending inwardly from the said head plate whereby upon inward adjustment of the said head plate toward the ad- 110 115 120 125 130

ja⁵cent end of the said casing the said pack-
ing masses are compressed.

4. In heat exchange apparatus, the combi-
nation of a casing, a plurality of tubes
5 therein, tube plates adjacent the opposite
ends of said casing having openings there-
through in which the opposite ends of the
said tubes are secured, one of said tube
plates being movable relative to the casing
10 and having means for spacing a portion of
its periphery from an adjacent portion of
the said casing, packing within the space be-
tween the periphery of said plate and the
said casing, a head plate adjustably secured
15 to the adjacent end of said casing, said head
plate having an inwardly extending flange
which is adapted to project into the said
casing, a member situated between said head
plate and said relatively movable tube plate,
20 the opposite ends of which terminate in an-
nular members, the inner of which extends
into the space between the periphery of the
said relatively movable tube plate and said
casing and contacts with the packing in said
25 space, and the outer of which is provided
with an external cut-away portion thereby
forming a space between the said outer por-
tion and the adjacent portion of said casing,
and packing within said space with which
30 the inner edge of the inwardly projecting
flange from the said head plate is adapted
to contact.

5. In heat exchange apparatus, the combi-
nation of a casing, a plurality of tubes
35 therein, tube plates situated near the oppo-
site ends of said casing, which plates are
provided with openings therethrough in
which the opposite ends of the said tubes
are secured, and one of the said plates being
40 movable relative to the casing, packing in-
termediate the periphery of said relatively
movable plate and the adjacent portion of
the said casing, a head plate having a flange
upon its inner side which is adapted to pro-
ject into the adjacent inner end of the said
45 casing, a member situated within the said
casing between the said head and the said
relatively movable tube plate, the inner and
outer ends of said member terminating in
50 annular portions which are connected by

spaced bars, the inner of said annular por-
tions being adapted to contact with the said
packing, and packing between the said outer
annular portion and said casing with which
the said inwardly extending flange upon the
55 said head plate is adapted to contact
whereby upon inward adjustment of the
said head plate the two portions of packing
are compressed.

6. In heat exchange apparatus, the combi-
nation of a casing, a plurality of tubes
therein, tube plates near the opposite ends
of said casing, which plates are provided
with openings therethrough in which the op-
posite ends of said tubes are secured, one of
60 said plates being movable relative to the
casing, packing interposed between the per-
ipheral portion of the latter plate and the
adjacent portion of the said casing, a mem-
ber situated within the said casing and hav-
ing an inner portion adapted to contact with
65 the said packing, packing interposed be-
tween a portion of the periphery of the
outer end portion of said member and the
said casing, and means whereby upon the
exertion of pressure upon the outer edge of
70 the last named packing the said packing is
forced outwardly against the said casing
while simultaneously the first named pack-
ing is forced inwardly against the periphery
of the said relatively movable tube plate.

7. In heat exchange apparatus, the combi-
nation of a casing, a plurality of tubes
therein, tube plates situated near the oppo-
site ends of said casing, which plates are
provided with openings therethrough in
85 which the opposite ends of said tubes are
secured, one of which plates is movable rela-
tive to the casing, packing between the per-
iphery of the said relatively movable plate
and the said casing, a head plate adjustable
90 axially of said casing, and means interposed
between said head plate and the said pack-
ing whereby upon inward adjustment of
said head plate the said packing is com-
pressed.

In testimony that I claim the foregoing
as my invention I have hereunto signed my
name this 26th day of March, A. D. 1923.

KARL MUHLEISEN.
